UNITED STATES PATENT OFFICE.

SAMUEL E. SPERRY, OF WOODHAVEN, NEW YORK, ASSIGNOR TO INTERTYPE CORPORATION, OF BROOKLYN, NEW YORK, A CORPORATION OF NEW YORK.

CASTING MECHANISM FOR TYPOGRAPHICAL MACHINES.

Application filed May 22, 1924. Serial No. 715,198.

To all whom it may concern:

Be it known that I, SAMUEL E. SPERRY, a citizen of the United States, residing at Woodhaven, in the county of Queens and 5 State of New York, have invented new and useful Improvements in Casting Mechanism for Typographical Machines, of which the following is a specification.

The present invention relates to improvements in the casting mechanism of typographical machines and more especially to machines of the linotype class substantially as shown and described in Letters Patent No. 436,532, granted September 16, 15 1890, to O. Mergenthaler and other machines employing a mold carried by a mold wheel or disk in which a type bar or slug is cast, and a metal pot for injecting the type metal into the mold, the mold wheel 20 being movable to carry the front face of the mold against an assembled line of matrices preparatory to the casting operation and the metal pot being movable to bring its mouth-piece against the rear face of the mold to 25 close it preparatory to the injection of type metal therein.

In machines of this class, the front face of the mold must fit evenly and very closely against the line of matrices which are held 30 in the casting position by the usual vise jaws and the mouth-piece of the metal pot must fit evenly and very closely against the rear face of the mold, otherwise leakage of molten type metal will occur at these points 35 when the molten metal is forced under pressure into the mold. Therefore, it has been the practice in constructing machines of this class to rigidly guide the mold wheel and metal pot in an effort to maintain the correct 40 relationship which is established between these parts when the machine is assembled. However, experience has shown that notwithstanding the care exercised in overcoming the difficulties of securing correct 45 alinement or lock-up of the mold wheel and metal pot, refitting or readjustment of these parts became necessary from time to time to correct the lack of alinement which developed, due to warping of these parts 50 or the parts of the machine on which they are mounted.

The present invention overcomes these difficulties, it providing novel and improved 55 mountings for the mold wheel and metal pot whereby these parts are free to aline

themselves with the line of matrices, thereby maintaining automatically a correct lock-up of these parts and accommodating them to warping or other changes which may take place in the machine.

To these and other ends the invention consists in certain improvements and combinations and arrangements of parts all as will be hereinafter more fully described, the features of novelty being pointed out particularly in the claims at the end of the specification.

In the accompanying drawings:—

Figure 1 is a top plan view, partly in section, of the first elevator containing a line 70 of matrices, the mold wheel and its slide and the metal pot, the mold wheel and metal pot being constructed and mounted in accordance with the present invention;

Figure 2 represents a vertical section 75 through the parts shown in Figure 1, the section being taken on the line 2—2 of said figure;

Figure 3 is a perspective view of a portion 80 of the metal pot and the means for mounting it in the machine;

Figure 4 is a diagrammatic view showing 85 the manner in which the mold wheel and metal pot are alined with the line of matrices.

Similar parts are designated by the same reference characters in the several views.

The present invention is applicable to typographical machines of the general class employing a mold wheel or its equivalent 90 and a metal pot for casting type bars or slugs from a line of matrices, although the invention is particularly applicable to machines of the linotype class as shown substantially in the patent hereinbefore referred to. The preferred embodiment of the invention is shown in the accompanying drawings and will be hereinafter described in detail. It is to be understood, however, that the invention is not restricted to the 95 precise construction shown, as equivalent constructions are contemplated, and such will be included within the scope of the claims.

In the present instance, 1 represents the 100 vise frame of a machine of the linotype class and 2 represents the so-called first elevator which embodies rails 3 adapted to receive a line of matrices M which have been 105 composed in the well-known manner to form 110

a line, the first elevator operating as is well known to lower the line of matrices to the casting level where the line is received between the usual vise jaws and is clamped 6 endwise preparatory to the casting operation. The matrices bear type characters in intaglio in their rear edges, as is usual in machines of this class, and the casting mechanism operates in the well known way to 10 cast a type bar or slug against the rear character-bearing edges of the matrices so that the type bar or slug thus produced bears type characters along its edge which are a reproduction of the type characters borne 15 by the assembled line of matrices. 4 is the mold wheel or disk carrying one or more molds 5 in which the type bars or slugs are cast. The mold wheel is carried by a slide 6 which is guided in the manner usual in 20 machines of this class, to reciprocate and thereby carry the mold 5 which is in use toward the line of matrices preparatory to a casting operation and to withdraw this mold from the line of matrices after the casting 25 operation has been performed. The mold wheel slide may be reciprocated at properly timed intervals by the usual cam on the cam shaft 7 of the machine. The mold wheel is revolvable in order that it may rotate after 30 each cast has been made, to effect trimming of the foot of the type bar or slug just cast in the mold and to bring the mold containing such type bar into position for ejection therefrom by the usual ejecting mechanism, 35 following which the rotation of the mold wheel is reversed and the mold in use is restored to operative position. To permit such rotation of the mold wheel to take place, it is mounted on a shaft 8 which is 40 journaled in a bearing 9.

Heretofore the bearing supporting the shaft of the mold wheel has been rigidly connected to the mold wheel slide and, hence, if the front face of the mold became out of 45 parallel with the rear face of a line of matrices held in the first elevator, due to warping of the parts of the machine, one end of the mold would engage the line of matrices in advance of the other end of the 50 mold, this lack of parallelism between the mold and the line of matrices precluding a sufficiently close fit between the front face of the mold and the matrices to withstand the pressure of the molten metal which is 55 forced into the mold, in consequence of which leakage of type metal would occur. The present invention provides a mounting for the mold wheel which renders it capable of self-alinement whereby an even and 60 very close fit between the front face of the mold and a line of matrices is insured, notwithstanding warping or other changes which may take place in the machine and which tend to alter the relationship between 65 the mold wheel and the matrix line support- ing means. Preferably, and as shown in the present instance, the bearing 9 which supports the mold wheel shaft is mounted on the mold wheel slide 6 so that the mold wheel may pivot or alter its angular position 70 about a vertical axis or an axis transverse to the length of the line of matrices. In the particular construction shown, the mold wheel slide 6 is formed with arms 10 which provide a forked bracket between which the bearing 9 is mounted, and these arms 10 receive trunnions or vertical pivots 11 which are secured in the bracket 9 and project from its upper and lower sides. This construction insures reciprocation of the mold wheel in unison with the reciprocations of the slide 6 in order to carry the mold in use toward and from a line of matrices preceding and following respectively each casting 80 operation, but the bearing 9 is free to pivot or rotate between the arms 10 on the mold wheel slide, this relative rotation taking place on a vertical axis or an axis which is transverse to the length of the line of matrices. Consequently, the front face of the mold will fit evenly against the rear face of the line of matrices, the pressure between the front face of the mold and the line of matrices being equalized throughout the 85 length of the line and, hence, the mold, as it comes into engagement with the line of matrices, preparatory to each casting operation, will accommodate itself to the position occupied by the line of matrices, it compensating for any variation in the relative position 90 between the line of matrices and the mold wheel, due to warping of the parts of the machine or other causes. A knife 12 similar to that usually employed, serves to trim the 95 foot of the slug or type bar cast in the mold, as the mold wheel rotates to bring the slug into position for ejection. This knife is rigidly supported by an arm 13 which is fixed to or forms a part of the mold wheel bearing 9, so that no alteration in the relationship 100 between this knife and the mold wheel will take place although the mold wheel may pivot on the pivot pins 11.

The present invention also provides improved means for mounting and shifting the metal pot whereby the mouth-piece of the latter will aline itself with the rear face of the mold and thus insure a proper lock-up therewith. In the present instance a metal pot 14 is shown which may be similar 115 to those commonly used in machines of this class, the metal pot being provided with a mouth-piece 15 which is adapted to fit against the rear face of the mold and is provided with orifices through which the molten type metal is injected into the cavity of the mold, and the metal pot also contains the usual plunger 16 which operates in well known manner to force molten metal from the metal pot through the mouth-piece 120 125 130

thereof and into the mold. The metal pot is shown housed, as usual, in a crucible 17 and the crucible is provided with legs 18 the lower ends of which are mounted or supported on a shaft 19 which may be the shaft commonly used to pivotally support the vise frame 1. As shown the lower ends of the legs 18 are formed with forks 20 which are adapted to straddle the shaft 19 and permit movement of these forked ends of the legs in a direction transversely and horizontally with respect to the shaft 19, a screw 20^a in the upper part of each fork bearing on a bushing 19^a on the shaft and thus serving as adjustable means to level and adjust the height of the mouth-piece of the metal pot with respect to the rear face of the mold. Means is provided for connecting the lower ends of the legs 18 to the frame of the machine in a manner which will permit a limited degree of movement of the forks 20 in opposite directions and crosswise of the shaft 19. As shown, a cross member 21 is secured to the rear sides of the legs 18 and this cross member is connected by a link 22 to a bracket 23, the latter being fixed to a suitable stationary portion 24 of the machine frame. The ends of the link 22 are preferably spherical in form and fit correspondingly shaped sockets 25 and 26, the link thus permitting universal movement to take place between the legs of the metal pot crucible and the machine frame.

35 In the operation of the machine, the metal pot is shifted to bring its mouth-piece against the rear face of the mold preparatory to each casting operation, and it is retracted following each casting operation. The means for so shifting the metal pot comprises an appropriately shaped cam 27 which is mounted on the cam shaft 7 of the machine, a bar 28 which carries a roller 29 which rides on and is actuated by the cam, and a bar or member 30 which is connected by a pin 31 to the upper end of the bar 28 and is connected at its forward end to the metal pot or the enclosing crucible 17 thereof by a pivot pin 32 which extends vertically and permits relative rotation between the bar 30 and the metal pot about the pin 32 as a vertical axis. This pivot pin 32 is substantially in vertical alinement with the pivot pins 11 which support the mold wheel as well as with the pivotal connection between the legs 18 and the stationary frame of the machine provided by the link 22, when the mouth-piece of the metal pot is in contact with the rear face of the mold, so that the mold wheel and the metal pot may freely swing bodily about the pivot pins 11 and 32, incident to the alinement of the front face of the mold with the line of matrices, without binding action between the metal pot mouth-piece and the rear

face of the mold. The cam 27, bar 28, roller 29 and member 30 operate to force the mouth-piece of the metal pot forwardly against the rear face of the mold 5 and to force the mold 5 together with the mold disk 70 forwardly to bring the forward face of the mold into contact with the rear face of the line of matrices, preparatory to each casting operation, the metal to form the slug being injected into the mold while the parts 75 are locked up in this manner. A spring 33 may be interposed between the lower end of the bar 28 and the metal pot crucible to compensate for over-motion of the cam, and the bar 28 may be provided at opposite sides 80 of the roller 29 with lugs or ears 34 to straddle the cam 27 and thereby guide the bar 28 and also insure proper tracking of the roller 29 on the cam. After the cast has been made, the low part of the cam 27 upon reaching the roller 29, allows the metal pot to swing rearwardly under its weight and about the shaft 19 as a center. By mounting the metal pot so that it will be free to swing or rotate about an axis substantially coincident with the vertical pivot pins 11 which support the mold disk, the mouth-piece of the mold pot will align itself with the rear face of the mold as it comes into engagement therewith preparatory to each casting operation, thus insuring an even tight fit at this point and thus avoiding leakage of the molten type metal which is forced under pressure into the mold.

35 In the operation of the machine, the metal pot is shifted to bring its mouth-piece against the rear face of the mold preparatory to each casting operation, and it is retracted following each casting operation. The means for so shifting the metal pot comprises an appropriately shaped cam 27 which is mounted on the cam shaft 7 of the machine, a bar 28 which carries a roller 29 which rides on and is actuated by the cam, and a bar or member 30 which is connected by a pin 31 to the upper end of the bar 28 and is connected at its forward end to the metal pot or the enclosing crucible 17 thereof by a pivot pin 32 which extends vertically and permits relative rotation between the bar 30 and the metal pot about the pin 32 as a vertical axis. This pivot pin 32 is substantially in vertical alinement with the pivot pins 11 which support the mold wheel as well as with the pivotal connection between the legs 18 and the stationary frame of the machine provided by the link 22, when the mouth-piece of the metal pot is in contact with the rear face of the mold, so that the mold wheel and the metal pot may freely swing bodily about the pivot pins 11 and 32, incident to the alinement of the front face of the mold with the line of matrices, without binding action between the metal pot mouth-piece and the rear

40 means for so shifting the metal pot comprises an appropriately shaped cam 27 which is mounted on the cam shaft 7 of the machine, a bar 28 which carries a roller 29 which rides on and is actuated by the cam, and a bar or member 30 which is connected by a pin 31 to the upper end of the bar 28 and is connected at its forward end to the metal pot or the enclosing crucible 17 thereof by a pivot pin 32 which extends vertically and permits relative rotation between the bar 30 and the metal pot about the pin 32 as a vertical axis. This pivot pin 32 is substantially in vertical alinement with the pivot pins 11 which support the mold wheel as well as with the pivotal connection between the legs 18 and the stationary frame of the machine provided by the link 22, when the mouth-piece of the metal pot is in contact with the rear face of the mold, so that the mold wheel and the metal pot may freely swing bodily about the pivot pins 11 and 32, incident to the alinement of the front face of the mold with the line of matrices, without binding action between the metal pot mouth-piece and the rear

45 means for so shifting the metal pot comprises an appropriately shaped cam 27 which is mounted on the cam shaft 7 of the machine, a bar 28 which carries a roller 29 which rides on and is actuated by the cam, and a bar or member 30 which is connected by a pin 31 to the upper end of the bar 28 and is connected at its forward end to the metal pot or the enclosing crucible 17 thereof by a pivot pin 32 which extends vertically and permits relative rotation between the bar 30 and the metal pot about the pin 32 as a vertical axis. This pivot pin 32 is substantially in vertical alinement with the pivot pins 11 which support the mold wheel as well as with the pivotal connection between the legs 18 and the stationary frame of the machine provided by the link 22, when the mouth-piece of the metal pot is in contact with the rear face of the mold, so that the mold wheel and the metal pot may freely swing bodily about the pivot pins 11 and 32, incident to the alinement of the front face of the mold with the line of matrices, without binding action between the metal pot mouth-piece and the rear

50 means for so shifting the metal pot comprises an appropriately shaped cam 27 which is mounted on the cam shaft 7 of the machine, a bar 28 which carries a roller 29 which rides on and is actuated by the cam, and a bar or member 30 which is connected by a pin 31 to the upper end of the bar 28 and is connected at its forward end to the metal pot or the enclosing crucible 17 thereof by a pivot pin 32 which extends vertically and permits relative rotation between the bar 30 and the metal pot about the pin 32 as a vertical axis. This pivot pin 32 is substantially in vertical alinement with the pivot pins 11 which support the mold wheel as well as with the pivotal connection between the legs 18 and the stationary frame of the machine provided by the link 22, when the mouth-piece of the metal pot is in contact with the rear face of the mold, so that the mold wheel and the metal pot may freely swing bodily about the pivot pins 11 and 32, incident to the alinement of the front face of the mold with the line of matrices, without binding action between the metal pot mouth-piece and the rear

55 means for so shifting the metal pot comprises an appropriately shaped cam 27 which is mounted on the cam shaft 7 of the machine, a bar 28 which carries a roller 29 which rides on and is actuated by the cam, and a bar or member 30 which is connected by a pin 31 to the upper end of the bar 28 and is connected at its forward end to the metal pot or the enclosing crucible 17 thereof by a pivot pin 32 which extends vertically and permits relative rotation between the bar 30 and the metal pot about the pin 32 as a vertical axis. This pivot pin 32 is substantially in vertical alinement with the pivot pins 11 which support the mold wheel as well as with the pivotal connection between the legs 18 and the stationary frame of the machine provided by the link 22, when the mouth-piece of the metal pot is in contact with the rear face of the mold, so that the mold wheel and the metal pot may freely swing bodily about the pivot pins 11 and 32, incident to the alinement of the front face of the mold with the line of matrices, without binding action between the metal pot mouth-piece and the rear

60 means for so shifting the metal pot comprises an appropriately shaped cam 27 which is mounted on the cam shaft 7 of the machine, a bar 28 which carries a roller 29 which rides on and is actuated by the cam, and a bar or member 30 which is connected by a pin 31 to the upper end of the bar 28 and is connected at its forward end to the metal pot or the enclosing crucible 17 thereof by a pivot pin 32 which extends vertically and permits relative rotation between the bar 30 and the metal pot about the pin 32 as a vertical axis. This pivot pin 32 is substantially in vertical alinement with the pivot pins 11 which support the mold wheel as well as with the pivotal connection between the legs 18 and the stationary frame of the machine provided by the link 22, when the mouth-piece of the metal pot is in contact with the rear face of the mold, so that the mold wheel and the metal pot may freely swing bodily about the pivot pins 11 and 32, incident to the alinement of the front face of the mold with the line of matrices, without binding action between the metal pot mouth-piece and the rear

65 means for so shifting the metal pot comprises an appropriately shaped cam 27 which is mounted on the cam shaft 7 of the machine, a bar 28 which carries a roller 29 which rides on and is actuated by the cam, and a bar or member 30 which is connected by a pin 31 to the upper end of the bar 28 and is connected at its forward end to the metal pot or the enclosing crucible 17 thereof by a pivot pin 32 which extends vertically and permits relative rotation between the bar 30 and the metal pot about the pin 32 as a vertical axis. This pivot pin 32 is substantially in vertical alinement with the pivot pins 11 which support the mold wheel as well as with the pivotal connection between the legs 18 and the stationary frame of the machine provided by the link 22, when the mouth-piece of the metal pot is in contact with the rear face of the mold, so that the mold wheel and the metal pot may freely swing bodily about the pivot pins 11 and 32, incident to the alinement of the front face of the mold with the line of matrices, without binding action between the metal pot mouth-piece and the rear

70 means for so shifting the metal pot comprises an appropriately shaped cam 27 which is mounted on the cam shaft 7 of the machine, a bar 28 which carries a roller 29 which rides on and is actuated by the cam, and a bar or member 30 which is connected by a pin 31 to the upper end of the bar 28 and is connected at its forward end to the metal pot or the enclosing crucible 17 thereof by a pivot pin 32 which extends vertically and permits relative rotation between the bar 30 and the metal pot about the pin 32 as a vertical axis. This pivot pin 32 is substantially in vertical alinement with the pivot pins 11 which support the mold wheel as well as with the pivotal connection between the legs 18 and the stationary frame of the machine provided by the link 22, when the mouth-piece of the metal pot is in contact with the rear face of the mold, so that the mold wheel and the metal pot may freely swing bodily about the pivot pins 11 and 32, incident to the alinement of the front face of the mold with the line of matrices, without binding action between the metal pot mouth-piece and the rear

75 means for so shifting the metal pot comprises an appropriately shaped cam 27 which is mounted on the cam shaft 7 of the machine, a bar 28 which carries a roller 29 which rides on and is actuated by the cam, and a bar or member 30 which is connected by a pin 31 to the upper end of the bar 28 and is connected at its forward end to the metal pot or the enclosing crucible 17 thereof by a pivot pin 32 which extends vertically and permits relative rotation between the bar 30 and the metal pot about the pin 32 as a vertical axis. This pivot pin 32 is substantially in vertical alinement with the pivot pins 11 which support the mold wheel as well as with the pivotal connection between the legs 18 and the stationary frame of the machine provided by the link 22, when the mouth-piece of the metal pot is in contact with the rear face of the mold, so that the mold wheel and the metal pot may freely swing bodily about the pivot pins 11 and 32, incident to the alinement of the front face of the mold with the line of matrices, without binding action between the metal pot mouth-piece and the rear

80 means for so shifting the metal pot comprises an appropriately shaped cam 27 which is mounted on the cam shaft 7 of the machine, a bar 28 which carries a roller 29 which rides on and is actuated by the cam, and a bar or member 30 which is connected by a pin 31 to the upper end of the bar 28 and is connected at its forward end to the metal pot or the enclosing crucible 17 thereof by a pivot pin 32 which extends vertically and permits relative rotation between the bar 30 and the metal pot about the pin 32 as a vertical axis. This pivot pin 32 is substantially in vertical alinement with the pivot pins 11 which support the mold wheel as well as with the pivotal connection between the legs 18 and the stationary frame of the machine provided by the link 22, when the mouth-piece of the metal pot is in contact with the rear face of the mold, so that the mold wheel and the metal pot may freely swing bodily about the pivot pins 11 and 32, incident to the alinement of the front face of the mold with the line of matrices, without binding action between the metal pot mouth-piece and the rear

85 means for so shifting the metal pot comprises an appropriately shaped cam 27 which is mounted on the cam shaft 7 of the machine, a bar 28 which carries a roller 29 which rides on and is actuated by the cam, and a bar or member 30 which is connected by a pin 31 to the upper end of the bar 28 and is connected at its forward end to the metal pot or the enclosing crucible 17 thereof by a pivot pin 32 which extends vertically and permits relative rotation between the bar 30 and the metal pot about the pin 32 as a vertical axis. This pivot pin 32 is substantially in vertical alinement with the pivot pins 11 which support the mold wheel as well as with the pivotal connection between the legs 18 and the stationary frame of the machine provided by the link 22, when the mouth-piece of the metal pot is in contact with the rear face of the mold, so that the mold wheel and the metal pot may freely swing bodily about the pivot pins 11 and 32, incident to the alinement of the front face of the mold with the line of matrices, without binding action between the metal pot mouth-piece and the rear

90 means for so shifting the metal pot comprises an appropriately shaped cam 27 which is mounted on the cam shaft 7 of the machine, a bar 28 which carries a roller 29 which rides on and is actuated by the cam, and a bar or member 30 which is connected by a pin 31 to the upper end of the bar 28 and is connected at its forward end to the metal pot or the enclosing crucible 17 thereof by a pivot pin 32 which extends vertically and permits relative rotation between the bar 30 and the metal pot about the pin 32 as a vertical axis. This pivot pin 32 is substantially in vertical alinement with the pivot pins 11 which support the mold wheel as well as with the pivotal connection between the legs 18 and the stationary frame of the machine provided by the link 22, when the mouth-piece of the metal pot is in contact with the rear face of the mold, so that the mold wheel and the metal pot may freely swing bodily about the pivot pins 11 and 32, incident to the alinement of the front face of the mold with the line of matrices, without binding action between the metal pot mouth-piece and the rear

95 means for so shifting the metal pot comprises an appropriately shaped cam 27 which is mounted on the cam shaft 7 of the machine, a bar 28 which carries a roller 29 which rides on and is actuated by the cam, and a bar or member 30 which is connected by a pin 31 to the upper end of the bar 28 and is connected at its forward end to the metal pot or the enclosing crucible 17 thereof by a pivot pin 32 which extends vertically and permits relative rotation between the bar 30 and the metal pot about the pin 32 as a vertical axis. This pivot pin 32 is substantially in vertical alinement with the pivot pins 11 which support the mold wheel as well as with the pivotal connection between the legs 18 and the stationary frame of the machine provided by the link 22, when the mouth-piece of the metal pot is in contact with the rear face of the mold, so that the mold wheel and the metal pot may freely swing bodily about the pivot pins 11 and 32, incident to the alinement of the front face of the mold with the line of matrices, without binding action between the metal pot mouth-piece and the rear

100 Fig. 4 indicates diagrammatically the manner in which the mold accommodates itself to the position occupied by the line of matrices in casting position, and the mouthpiece of the metal pot accommodates itself to the position assumed by the mold as it comes into contact with the line of matrices, the full lines indicating, to an exaggerated extent, a lack of alinement or parallelism between the mold and the line of matrices, and between the mold and the mouthpiece of the metal pot, and the dotted lines showing these parts properly alined incident to their coming into contact with one another.

105 By pivotally mounting the mold wheel on its slide, substantially as has been described, the mold is rendered capable of adjusting itself angularly with respect to the length of the line of matrices held in the casting position, thereby bringing the front face of the mold into even and close fit with the character bearing edges of the matrices comprising the line; and by mounting the metal pot so that it may alter the angular position of its mouthpiece in the direction of its length and forcing the mouthpiece against the rear face of the mold by a member which pivotally engages the metal pot at a point intermediate the length of the mouthpiece, the mouthpiece will adjust itself evenly and

110

115

120

125

130

very closely against the rear face of the mold. Thus a tight lock-up between the front face of the mold and the line of matrices and the rear face of the mold and the mouthpiece of the metal pot is always insured, notwithstanding warping and other influences which, in machines of this class as heretofore constructed, have caused leakage of the molten type metal at one or both of these points.

I claim as my invention:

1. In a typographical machine of the class described, the combination with means for holding a line of matrices in casting position, of a mold wheel operative to present the face of a mold thereon to the character-bearing face of the line of matrices and supported on a fixed vertical axis which extends transversely of the mold at a point substantially centrally of its length, whereby the mold wheel is prevented from rocking in a vertical plane but is free to rock in either direction about said axis when the mold comes into contact with said face of the line of matrices, to insure intimate contact between the line of matrices and said face of the mold.

2. In a typographical machine of the class described, the combination with means for holding a line of matrices in casting position, of a mold wheel carrying a mold which is movable into closing relation with the line of matrices, the mold wheel being pivotally mounted on a fixed axis which intersects the center of rotation of the mold wheel to allow either end of the mold thereon to swing toward the face of the line of matrices about such axis, but supports the mold against swinging in other directions whereby the alinement of the mold with the line of matrices, during the final part of the closing movement of the mold, is controlled by the line of matrices.

3. In a typographical machine of the class described, the combination with means for holding a line of character-bearing matrices in casting position, of a mold movable into contact with the character-bearing face of the line of matrices in making a cast therefrom, the mold being pivoted on a fixed vertical axis which is transverse to and located substantially centrally of the length of the mold whereby the mold may aline itself longitudinally with said face of the line of matrices when brought into contact therewith but is supported by said axis against rocking movement in a vertical plane.

4. In a typographical machine of the class described, the combination with means for holding a line of character-bearing matrices in casting position, of a mold movable to bring it into contact with the character-bearing face of the line of matrices preparatory to the making of a cast therefrom,

mold being capable of pivoting movement about a fixed axis which is located substantially centrally of the length thereof whereby it may adjust its face into longitudinal parallelism with the character-bearing face of the line of matrices.

5. In a typographical machine of the class described, the combination with means for holding a line of matrices in casting position, of a mold adapted to be brought into contact with the line of matrices, the mold being pivotally supported on a fixed vertical axis which is transverse to the length of said line and is located substantially centrally between the ends of the mold whereby the face of the mold may adjust itself into longitudinal parallelism with the cooperative face of the line of matrices when the mold is brought into contact therewith.

6. In a typographical machine of the class described, the combination with means for holding a line of matrices in casting position, of a mold wheel carrying a mold adapted to be brought into casting relation with the line of matrices, the mold wheel being pivotally supported on a fixed vertical axis which is transverse to the length of the line of matrices and is located substantially centrally of the length of the mold, thus enabling the mold to rock in either direction about said axis and thereby adjust itself in conformity with the position occupied by the line of matrices.

7. In a typographical machine of the class described, the combination with means for holding a line of matrices in casting position, of a reciprocating slide, a rotatable mold wheel having a supporting bearing which is pivotally supported on the slide on a fixed axis which intersects the center of said bearing and carrying a mold which is adapted to be brought into casting relation with the line of matrices by the movement of the slide, said axis extending transversely to and being located substantially centrally of the length of the mold whereby the latter is capable of adjusting itself to the line of matrices by relative pivoting movement between the mold wheel and the slide on said axis.

8. In a typographical machine of the class described, the combination with means for holding a line of matrices in casting position, of a reciprocating slide, a rotatable mold wheel having a bearing which is pivotally supported on the slide on an axis transverse to the direction of reciprocation thereof and carrying a mold to cooperate with a line of matrices held in casting position, and an arm rigidly connected to said bearing and supporting a device to trim the foot of a type slug cast in the mold.

9. In a typographical machine of the class described, the combination with means for holding a line of matrices in casting posi-

tion, of a mold movable into closing relation with the character-bearing face of the line of matrices and capable of rocking about an axis located substantially centrally between its ends to adjust itself to said line, and a metal pot having a mouthpiece movable into closing relation with the mold to inject metal therein, said mouth piece being mounted to rock about an axis located approximately in the same plane with its mold engaging face and capable of adjusting the mold and itself to the line of matrices during the final part of its closing movement.

10. In a typographical machine of the class described, the combination with means for holding a line of matrices in casting position, of a mold movable into closing relation with the line of matrices and mounted pivotally whereby it may adjust itself to the position occupied by the line of matrices, and a metal pot movable to bring its mouth-piece into closing relation with the mold, said mouth piece being mounted pivotally on an axis transverse to and located substantially centrally of its length, said axis being located approximately in the same plane with the mold engaging face of the mouth piece, whereby the alinement of the metal pot mouth-piece and the mold with the line of matrices, during the final part of the closing movement of these elements is controlled by the line of matrices.

11. In a typographical machine of the class described, the combination with means for holding a line of matrices in casting position, of a mold wheel carrying a mold movable into cooperation with the line of matrices, and a metal pot having a mouth-piece movable into cooperation with the mold, the mold wheel and metal pot being pivoted on substantially coincident axes which extend transversely of the length of the mold and are located substantially centrally of the

length thereof whereby the relationship of the metal pot mouth-piece and the mold to one another and to the line of matrices, during the final part of the relative movement between these elements to bring them into cooperation, is determined by the position of the line of matrices.

12. In a typographical machine of the class described, the combination with means for holding a line of matrices in casting position, of a mold wheel carrying a mold to cooperate with the line of matrices and a metal pot having a mouth-piece, to cooperate with the mold, the mold wheel and metal pot being pivotally mounted on a substantially common axis arranged transverse to the length of the line of matrices.

13. In a typographical machine of the class described, the combination with means for holding a line of matrices in casting position, and a mold to cooperate therewith, of a metal pot having a mouth-piece to cooperate with the mold, the metal pot being movably mounted whereby it may adjust itself to the mold, and means including a member connected to the metal pot on an axis transverse to the length of the mold, for forcing the mouth-piece of the metal pot against the mold.

14. In a typographical machine of the class described, the combination with a mold of a metal pot having a mouth-piece to cooperate with the mold, the metal pot being movably mounted whereby it may adjust itself angularly with respect to the length of the mold, and means including a member pivotally acting on the metal pot at a point intermediate the length of the mouth-piece for forcing the mouth-piece against the mold.

In testimony whereof I have hereunto set my hand.

SAMUEL E. SPERRY.
